United States Patent Office.

WILLIAM PARKIN, OF TAUNTON, MASSACHUSETTS, ASSIGNOR TO REED & BARTON, OF SAME PLACE.

Design No. 3,877, dated March 1, 1870.

DESIGN FOR A CAKE-BASKET OR FRUIT-TRAY.

The Schedule referred to in these Letters Patent and making part of the same.

To all persons to whom these presents may come:

Be it known that I, WILLIAM PARKIN, of Taunton, of the county of Bristol, and State of Massachusetts, have invented a new, useful, and ornamental Design for a Cake-Basket or Fruit-Tray; and do hereby declare the same to be represented in the accompanying drawings, of which—

Figure 1 is a side elevation, and

Figure 2, an end view of it.

The body A is of a frusto-pyramidal form, having its upper edge beaded and shaped in manner as exhibited in figs. 1 and 2.

At the middle and upper part of each end and side of the body is a trefoil, a, over which is a projection, b, to which a handle, B, is pivoted.

From each corner of the body, and at the lower

part thereof, is a bracketed leg, C, supporting the figure of a child, having one leg crossed on the other, the form of such bracketed leg being as shown in the drawings.

The handle is surmounted by a bust, D, such handle and bust being shaped as exhibited in the figure. The handle and its bust are to be viewed as auxiliaries to the design for the tray, such design consisting in the body, the bracketed legs, and the figures supported by the latter.

I claim the said described and represented design for a cake-basket or fruit-tray.

WILLIAM PARKIN.
